UNITED STATES PATENT OFFICE.

JOHN CARL KLAHN, OF BERLIN, ONTARIO, CANADA, ASSIGNEE, BY MESNE ASSIGNMENTS, TO CANADIAN CONSOLIDATED RUBBER COMPANY, LIMITED, OF MONTREAL, CANADA, A CORPORATION.

VULCANIZING APPARATUS.

1,087,589.

Specification of Letters Patent.

Patented Feb. 17, 1914.

Application filed January 9, 1911. Serial No. 601,693.

To all whom it may concern:

Be it known that I, JOHN C. KLAHN, of Berlin, in the Province of Ontario, Dominion of Canada, have invented certain new and useful Improvements in Vulcanizing Apparatus; and I do hereby declare that the following is a full, clear, and exact description thereof.

My invention relates to vulcanizing machines of the type wherein a multiplicity of articles such as rubber shoes are simultaneously vulcanized while mounted on a common carrier; and it may be said briefly to consist of a heating appliance and a carrier for the articles to be vulcanized, the carrier being made to revolve around the heating appliance and present successively thereto the different sides of each article being vulcanized for the purpose of securing uniform vulcanization. For full comprehension, however of my invention, reference must be had to the accompanying drawings forming a part of this specification, in which similar reference characters indicate the same parts, and wherein:—

Figure 1, is a diagrammatical horizontal sectional view of a pair of vulcanizing chambers containing my invention; Fig. 2 is a transverse vertical sectional view taken in line A, A, Fig. 1 and with a portion of the adjacent wall broken away; and Fig. 3 is a longitudinal sectional view illustrating particularly the detail construction of my improved carrier and heating appliance, one end only thereof being shown.

The vulcanizing chamber is preferably divided into two parts or ovens *b* and *c*, and within each is revolvably mounted a skeleton drum comprising a pair of wheels 2, mounted upon a shaft 3 passed through both ovens, and stay rods 13 uniting the wheels together, the wheels constituting the ends of the drums and being mounted rigidly on the shaft which also has a pair of miter gears 45 fixed rigidly thereto and driven by any suitable means, indicated at 5, and preferably including a reduction gear to secure rotation of the drums at a low speed.

Each drum has an annular series of stick-carriers 6, revolvably mounted thereon, and encircling an electric heater 7 secured rigidly upon the shaft which is made hollow at both ends of each oven, the wires 8 and 9 of the

heating circuit being taken to the heater through the interior of the hollow ends of the shaft. Two pairs of commutators 50 with brushes 51 and 52 are mounted on the shaft at each end of the chamber and are fed from any available source of electric supply indicated at 53.

10 and 12 indicate rheostats for controlling the flow of the heating current to regulate the temperature within the ovens.

The stick carriers are made to maintain the sticks carried thereby and the lasts 65 mounted on the sticks constantly in horizontal or level position by pulleys 14 mounted rigidly upon the latter, a pulley 15 mounted rigidly upon the wall of the oven, a pulley 16 mounted rotatably on the frame of the 76 drum, and an endless belt 17 looped around all the said pulleys.

The sticks, indicated at 20 are mounted in notched racks 21 fixed upon the carriers 6; the sticks and notched racks, *per se*, being 75 well known to those skilled in the art of manufacturing rubber shoes and the like, are not described in detail.

Operation: The sticks having the lasted shoes mounted thereon are set in place in 80 the notched racks on the carriers 6, and when the apparatus is started the belt 17 will drag on the fixed pulley 15 and hold the pulleys 14, and, consequently, the stick carriers against rotation on their axes, thus 85 maintaining the latter with the rows of sticks constantly in the same horizontal plane. The effect is that as the drum rotates and the stick carriers revolve with it the different points in the circumference of 90 each carrier will be successively presented to the heater, and much more uniform vulcanization secured, owing to the central location of the heater, than has been possible heretofore.

95 What I claim is as follows:—

1. In a vulcanizing apparatus the combination with a heater, an annular series of stick carriers encircling the heater and consisting of carrier members proper and means 100 for attaching the sticks thereto; means for causing the series to revolve; and means acting upon the carriers for maintaining the same in level position during revolution.

2. In a vulcanizing apparatus the combination with an electric heater, an annular

2
series of stick carriers encircling the heater and consisting of carrier members proper and means for attaching the sticks thereto; means for causing the series to revolve; and
5 means acting upon the carriers for maintaining the same in level position during revolution.

In testimony whereof, I have signed my name to this specification, in the presence of two subscribing witnesses.

JOHN CARL KLAEHN.
